GREASE PUMP

Harry Balshaw Caldwell, Penketh, England, assignor to Electro-Hydraulics Limited, Warrington, England, a company of Great Britain

Application September 9, 1948, Serial No. 48,351
In Great Britain August 20, 1947

5 Claims. (Cl. 184—35)

1

This invention relates to grease pumps and concerns more especially the use of a pump in a greasing system, wherein different parts of a machine have to be lubricated from a single point. As an example of machines in which this type of system is particularly useful it will be appreciated that the invention is applicable to machine tools, motor cars and parts thereof.

In a known system a grease pump is provided with a single outlet which is branched out into a number of pipes leading to the several parts of the system to be lubricated. This arrangement has the disadvantage that the pipes having the lowest resistance to flow of grease, either due to short length thereof or to the pipe being unobstructed, will receive most of the lubricant from the pump. The parts of the system remote from the pump outlet or pipes having a higher resistance to flow of lubricant leading to such parts whether clear or containing a foreign matter capable of resisting the flow of lubricant and even becoming plugged so as to stop said flow, may often remain without lubricant although the grease pump has been actuated. Increased resistance against the pressure of the pump in some lines may not necessarily be detected since the other lines of low resistance or unobstructed lines, will take up the lubricant, and thus there is always the possibility of a breakdown in the lubricating of the necessary parts.

It is an object of the present invention to provide a grease pump which, when operated, will allow the pump outlet to be connected in a pre-determined sequence to each of the pipe lines leading to the parts to be lubricated.

According to the present invention a grease pump comprises a lubricant receiving cylinder within the pump body, a piston slidably in said cylinder, a valved outlet from said cylinder communicating with a pipe line selector within the pump body, which selector on actuation of the piston is rotatable through a pre-determined distance to place the outlet from the selector successively in communication with one of the pipe lines leading to the parts to be lubricated, so that lubricant is forced into each pipe line in turn.

Preferably the selector is moved through a pre-determined distance positively by actuation of the piston through, for example, a pawl engaging a ratchet mechanism fast with the selector. Preferably also the piston is actuated against the action of a spring, whilst the outlet from the cylinder is controlled by a non-return valve. The ratchet teeth are provided preferably in number equal to the number of pipe lines.

The invention is illustrated in the accompanying drawings in which Figure 1 illustrates one form of pump, Figure 2 being a section on the line A—A. Figure 1, Figure 3 is a longitudinal

2

section of a modified form of pump, Figure 4 being a part-section taken at right angles, and Figure 5 a sectional plan view on the line 5—5 Figure 3. Figure 6 is a similar view on the line 6—6 Figure 4, Figure 7 being a part view similar to Figure 3 but with the piston in the operative position, Figure 8 a sectional plan on the line 8—8 Figure 7, Figure 9 is an elevational view partly in section showing a spring loaded lubricant accumulator in place, and Figure 10 is a similar view of the pump equipped with a transparent cover for rendering the indicia on the ratchet wheel visible.

Referring to the construction shown in Figures 1 and 2 the pump body 1 has slidably mounted in its bore 2 a piston 3 which is rendered fluid-tight by any suitable means for example a suitable packing or fit. The piston 3 terminates in a flanged head 4, outside the body, which head constitutes the piston operating portion and the piston 3 is actuated against the load of a spring 5 for example by hand or foot pressure. The cylinder is provided with an inlet 6 to enable lubricant to enter either under suction when the piston is moved, or by the provision of a low pressure lubricant accumulator such as shown in Figure 9, to feed the pump cylinder according to requirements. The cylinder is formed with a large recess 7 into which the lubricant is fed from the inlet 6, the recess communicating through a non-return valve 8 biassed to closed position by a spring 9, through a passage 10 into the centre of a stepped bore 11 within the pump body. Mounted within the smaller diameter of the said bore is a rotary selector 12 which carries in any convenient manner, for example by brazing, a ratchet wheel 13 which is capable of rotation within the larger diameter part of the stepped bore. The number of ratchet teeth provided on the wheel 13 correspond to the number of outlet ports in the pump body, each of which ports communicates with a pipe line leading to a part to be lubricated. The passage 10 communicates through a port 14 into a U-shaped bore 12' of the rotary selector 12, which bore allows communication from the passage to one of the outlet port holes, two of which are shown at 15 and 16 (Figure 2) and thence to the pipe lines, which serve as means to carry the lubricant to the required points. A plate 18 is arranged to hold in position double conical hollow sealing washers 19 and is secured onto the pump body 1 by bolts 20. Pivotally mounted upon the piston rod is a pawl 21 which is adapted to engage with the ratchet wheel 13, the pump casing being enclosed by a cover 22 provided with suitable packing 23.

It will be appreciated that by moving the piston 3 against the action of its spring 5, that is to say into the cylinder 1 the piston forces lubricant past the non-return valve 8 into the passage

10 leading to the rotary selector 12, past one of the ports 15, 16 into one of the outlet pipe lines 17. When pressure on the piston is released the spring 5 returns the piston to its former position and the return stroke of the piston allows the pawl 21 to drive the ratchet wheel 13 conveniently by one tooth pitch; thus the rotary selector 12 is rotated by the same amount, thereby bringing the U-shaped bore 12' therein into communication with the next pipe line in succession.

In order to provide an indication for the outlet pipe connected to receive lubricant, the ratchet wheel and the pipe lines can be numbered, and an eccentric or cam may be provided on the selector with a cable connecting the eccentric or cam to a remote indicator. If desired, the pump body may be provided with an opening having a transparent cover 14, so that the number on the ratchet wheel is rendered visible as shown in Figure 10; moreover the pipes 17 may be non-metallic and/or transparent so that pumping action can be checked from outside and also to guard against the effects of vibration. As has been stated above the lubricant may be fed to the pump cylinder by a low pressure lubricant accumulator and if this arrangement be provided the accumulator may contain a spring-loaded piston thus ensuring that the pump is loaded. One form of a low pressure lubricant accumulator is shown in Figure 9 wherein 61 represents the accumulator cylinder fastened to the pump body 1 by means of a threaded stem which fits in the inlet 6 and places the accumulator cylinder in communication with the cylinder of the pump body 1. The accumulator cylinder 61 is closed by a threaded cap 62 and has located therein the piston or plunger 64 normally under a downward pressure from a coil spring 63 interposed between the plunger and the cap 62. Suitable packing 65 secured to the plunger 64 by means of a central bolt and nut 66 insures against leakage of lubricant past the plunger 64.

Referring now to the modified form shown in Figures 3 to 8 parts similar to those provided in the previous construction are given the same reference numerals. In the pump body 1 again slides the piston 3, a sealing gland 3' being provided to seal the port through the pump body. Fixed to the piston 3 by means of washer 24 and circlip 25 is a collar 26 having a radially projecting arm 26a as will be seen from Figure 3. The inner end of the piston 3 slides in the bore 2 which is provided with apertures 27. Carried by or integral with the cylinder 1 is the rotary selector 12 and ratchet wheel 13, the outlet of the cylinder being closed again by the non-return valve 8 and spring 9. An aperture 28 in the cylinder 1 and selector 12 communicate with a single outlet port 29 which may be provided with a washer 30 or a flanged tube resiliently backed up, for example, by one or more rubber rings. The selector carries a further dummy port and washer on its opposite side to prevent tilting when under pressure. The pump body 1 is provided with an inlet connection 6 and is closed by a cover 31 which has a number of outlets 17 preferably corresponding to the number of teeth of the ratchet wheel 13. The outlets 17 carry on their inner ends double conical hollow sealing washers 19 which are held in position by the securing nuts 20 screwed into the end plate 18, which in turn is retained in the body 1 by a circlip 13. Surrounding the piston 3 and the bore 2 is a lever 32 in the form of a yoke the shape

of which is seen more particularly in Figures 4, 5 and 6. This yoke 32 is pivotally mounted intermediate its ends on bolts 33, 34 screwed into the pump body 1, and is also pivotally connected at one end to a pin 35 of a trunnion 36 as shown in Figure 3. A spring 37 is held in position by a spring support 38 which in turn is in fixed connection with the pump body 1 through a bracket 39 and nut 40. The said spring 37 biasses the trunnion 36 into the position shown in Figure 3, the load of the spring being adjustable by means of a bolt 41 screwing into the pump body and a lock nut 42. Fixed to the yoke 32 is a pin 43' to which is rotatably mounted the pawl 21 which may be held in engagement with the ratchet teeth by any suitable spring (not shown). A spring 44 biasses the collar 26 and with it the piston 3 into the position shown in Figure 3 and the other end of the spring 44 rests on the ratchet wheel 13, the ball race or a number of washers 45 being interposed between the spring and the ratchet wheel so that movement of the ratchet wheel does not increase the tension of the spring. The piston is again shown with an actuating knob 4 although it will be appreciated that the piston could be operated by other means such, for example as being operated through a motor. As will be seen from Figures 3 and 7 the inner surface of the yoke 32, adjacent the radial arm on collar 26, is arcuate in vertical cross section, so as to effect a cam action with said arm as the piston and collar are moved inwardly as in Figure 7. This cam action causes the yoke 32 to rock clockwise on the bolts 33, 34, elevating the trunnion 36 against the bias of spring 37 and positioning the pawl 21 for engagement with the succeeding tooth of the ratchet 13. Upon return of the piston to its original position, the spring 37 rocks the yoke 32 counterclockwise and with it, the pawl 21 which, through ratchet 13, rotates the selector 12 to the next position. Before further describing the operation of this modification it must be stated that in Figures 7 and 8 the piston 3 and yoke 32 are shown in the depressed position that is to say the position in which they are moved to deliver lubricant.

The system works as follows: the bore of the pump body is filled with lubricant through the connection 6 by known means, for example an accumulator with a spring-loaded piston. When the piston 3 is depressed the lubricant in the cylinder bore 2 between the piston 3 and the non-return valve 8 will be forced through the aperture 28 and port 29 into a pipe line 17. As the collar 26 is fixed to the piston 3 on movement of the piston the radial arm 26a of collar 26 will carry the yoke 32 with it thus pivoting the yoke around the bolts 33, 34 carrying the trunnion 36 into the pump body. When the load on the piston is removed the spring 44 will return the piston to its original position and the spring 37 will return the trunnion 36 to its original position, the latter carrying the yoke 32 with it due to its connection by the pin 35. The tip of the pawl 21 will advance by one tooth of the ratchet 13 during the upward stroke of the piston 3 as shown in Figure 8, and when the trunnion 36 returns the yoke 32 due to the action of the spring 37 the pawl 21 will pivot round its pin 43' and move the ratchet wheel 13 and with it the rotary selector 12 by one tooth and connect the port 29 with the next pipe line.

What I claim is:

1. A grease pump the outlet of which is adapted to be connected in a pre-determined sequence to

each of a number of pipe lines leading to the parts to be lubricated, and comprising a pump body, a lubricant receiving cylinder within said pump body, a piston and piston rod slidable in said cylinder, the piston rod extending externally of the pump body to form means for actuating the piston, a valved outlet from said cylinder, a rotatable pipe line selector, within the pump body, and communicating with said cylinder, a number of pipe lines, a ratchet mechanism fast with the selector and within the pump body, a pawl pivotally mounted for actuation by said piston rod for engagement with said ratchet mechanism, so as positively to move the selector, step by step, a pre-determined distance governed by said pawl and ratchet mechanism to place the selector outlet successively in communication with one of the pipe lines, leading to the parts to be lubricated, so that lubricant is forced into each pipe line in turn.

2. A pump as claimed in claim 1 wherein the lubricant receiving cylinder is fed from an accumulator containing a spring loaded piston, a non-return valve being provided in the outlet from said cylinder.

3. A grease pump comprising a main body, a lubricant cylinder within said body, a piston slidable in the cylinder, a piston operating rod extending from said body, a lubricant inlet to said cylinder, a valved outlet from said cylinder, means in said body for receiving the inlet end of each of a series of pipe lines leading to the points to be lubricated, a pipe line selector rotatably mounted within said body adjacent said last-named means and having a passageway in communication with said cylinder, through said outlet, the outlet of said passageway being arranged to successively communicate with individual pipe lines as the selector is rotated, a ratchet fast with said selector and within said pump body, a spring

biased yoke fulcrumed intermediate its ends in said body, adjacent said piston rod, a pawl on said yoke, adapted for engagement with said ratchet, co-acting cam elements on said piston rod and yoke respectively, for rocking the latter on its fulcrum, against the force of said biasing spring, upon inward longitudinal movement of the piston, whereby said pawl is positioned for engagement with a succeeding tooth on said ratchet, the return movement of said piston releasing the yoke and causing the rotation of said selector to its next position.

15 4. A pump as claimed in claim 3 wherein one of said co-acting cam elements comprises a collar fixed on said piston rod and having a projection which operatively engages a complementary cam element carried by said yoke.

20 5. A pump as claimed in claim 3 wherein said yoke surrounds said piston and is fulcrumed intermediate its ends in said body, on an axis transverse to that of said piston, one of said co-acting cam elements comprising a collar fixed on said piston rod and having a projection which operatively engages a complementary cam element carried by said yoke.
